UNITED STATES PATENT OFFICE.

MARY ELISE JUERGENS, OF CHICAGO, ILLINOIS.

MACHINE FOR USE IN CULINARY OPERATIONS.

SPECIFICATION forming part of Letters Patent No. 769,169, dated September 6, 1904.

Application filed March 2, 1904. Serial No. 196,179. (No model.)

To all whom it may concern:

Be it known that I, MARY ELISE JUERGENS, a citizen of the United States, residing at Chicago, in the county of Cook and State of Illinois, have invented new and useful Improvements in Machines for Use in Culinary Operations, of which the following is a specification.

This invention relates to devices for use in culinary operations; and its object is to provide a machine for mixing batter, beating eggs, churning butter, and similar procedures in which one or more food ingredients are agitated or commingled.

15 The invention consists in a liquid-tight receptacle in which is a wheel rotating on a horizontal axis and having peculiarly-constructed arms. The wheel is mounted on a shaft, which projects through the walls of the receptacle, and is provided with a crank-handle, by which the shaft and the wheel can be rotated. The bottom of the receptacle is rounded, and at its lowest point a gate is provided to permit the contents to be drawn off.

25 In the accompanying drawings, Figure 1 is a perspective view of my machine. Fig. 2 is a vertical section of the same. Fig. 3 is a perspective view of one arm of the agitator-wheel. Fig. 4 is a longitudinal section of the 30 hub of said wheel.

The receptacle 1 is made of sheet metal in the form of a rectangular box, supported on legs 2 and provided with handles 3 for carrying it. The bottom is preferably rounded on a 35 curve concentric with a shaft 4, which extends across from front to rear and is journaled in bearings in one or more stiffening-ribs 5 on the outer face of the front and rear walls. One end of the shaft has a crank-handle 4'. At the lowest part of the receptacle and preferably projecting from the front wall is a spout 6, above which is a sliding gate 7, which closes an opening in the receptacle coinciding with said spout.

45 Inside the receptacle is a rotatable agitator or wheel comprising a hub 8, through which the shaft 4 passes and to which it is removably secured by set-screws 9 or otherwise. From the hub radiate a plurality of arms each consisting of a strip 10 of thin material, such as

sheet metal having one or more openings in it, and adjacent to each opening is a blade 11, standing obliquely to the plane of the strip, but parallel with the axis of rotation and preferably containing one or more holes 12. The 55 blade is preferably made by bending outwardly the metal cut out to form the opening. The inner end of the strip is preferably bent to form a flange 13, by which it can be soldered to the hub 8. The edges of the strip 60 are suitably stiffened, preferably by doubling over the sheet metal. The outer end of the strip is secured to two circular hoops 14, preferably of wire. The preferred mode of fastening the strips to the hoops is by bending 65 the end of the strip to form a flange 15 and then curling the ends of said flange around the hoops, as shown at 16.

The mode of operation is as follows: The lid 17 is lifted off and the batter, eggs, milk, 70 or other substance or mixture to be operated on is put into the receptacle. The lid is then replaced, and the crank-handle 4' is turned to rotate the wheel. The openings in the radial arms permit the contents of the receptacle to 75 pass through them; but the oblique perforated blades occasion cross-currents, which quickly break up and commingle the contents and soon reduce them to the proper consistency. The gate 7 is then lifted to permit the contents to run out into a dish or pan. By loosening the set-screws 9 the shaft can be pulled 80 out, and the wheel can then be removed for cleaning.

Having thus described my invention, what 85 I claim is—

1. In a machine of the class described, the combination with a receptacle, of a rotatable agitator therein, comprising radial arms each consisting of a strip of material having openings and a transverse flange at its outer end, and hoops lying in planes parallel with the edges of the arms and engaged by the ends of said flanges.

2. In a machine of the class described, a rotatable agitator comprising radial arms each consisting of a strip of material having openings therein and oblique blades each having one edge coincident with the edge of an opening and parallel with the axis of rotation.

3. In a machine of the class described, a rotatable agitator having radial arms each composed of a strip of sheet metal with doubled edges, and a transverse flange at each end, 5 having portions cut and bent to form oblique blades adjacent to transverse openings.

4. In a machine of the class described, a rotatable agitator having radial arms each composed of a strip of sheet metal with doubled 10 edges and a transverse flange at each end, and

having portions cut and bent to form oblique blades adjacent to transverse openings, said blades having perforations.

In testimony whereof I have signed my name to this specification in the presence of two sub- 15 scribing witnesses.

MARY ELISE JUERGENS.
